(57) **CLAIM**

The ornamental design for an angle grinder, as shown and described.

DESCRIPTION

FIG. 1 is a perspective view of an angle grinder showing my new design;

FIG. 2 is a side view thereof;

FIG. 3 is the opposite side view of FIG. 2 thereof;

FIG. 4 is a front view thereof;

FIG. 5 is a rear view thereof;

FIG. 6 is a top view thereof; and

FIG. 7 is a bottom view thereof.

FIG. 8 is a top perspective view of a second embodiment of an angle grinder—showing my new design;

FIG. 9 is a side view thereof;

FIG. 10 is the opposite side view of FIG. 9 thereof;

FIG. 11 is a front view thereof;

FIG. 12 is a rear view thereof;

FIG. 13 is a top view thereof; and,

FIG. 14 is a bottom view thereof.

The broken line showing of the interior elements of the angle grinder head forms no part of the claimed design.
